UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

THREAD-CONTROLLING MECHANISM FOR SEWING-MACHINES.

1,129,586.

Specification of Letters Patent.

Patented Feb. 23, 1915.

Application filed October 8, 1906. Serial No. 337,991.

To all whom it may concern:

Be it known that I, LANSING ONDERDONK, a citizen of the United States, residing at New York, in the county of New York, 5 State of New York, have invented certain new and useful Improvements in Thread-Controlling Mechanism for Sewing-Machines, of which the following is a description, reference being had to the accompanying drawing and to the letters and figures 10 of reference marked thereon.

My invention relates to improvements in thread controlling mechanism for sewing machines, and while as to some of its features it may be used for various purposes, 15 said improvements are more particularly adapted to machines for making chain stitches.

The object of my invention is to provide 20 a thread controlling mechanism which will care for the slack formed by the looper in both its forward and backward movements.

A further object of my invention is to provide a thread controlling mechanism 25 which includes a pull off controlled in its movements by the feed of the machine.

These and other objects of the invention will in part be obvious and in part be more fully explained hereinafter.

30 My invention consists in the novel parts, improvements and combinations hereinafter shown and described.

In the accompanying drawings I have illustrated one embodiment of my invention, 35 the same serving, in connection with the description herein to illustrate the principles thereof.

Figure 1 is a front elevation of the lower portion of a sewing machine with my improvements applied thereto, certain parts being shown in section. Fig. 2 is a top plan view of the parts shown in Fig. 1, the bed plate being removed and the feed dog broken away to more clearly show the looper and 45 thread controlling mechanism. Fig. 3 is a transverse sectional elevation of the parts as shown in Fig. 1. Fig. 4 is a detail perspective view of my looper mechanism, also showing a portion of the thread controlling 50 mechanism. Fig. 5 is a detail perspective view of the auxiliary thread controller with the thread engaging member in the position it occupies when the looper is at the rear portion of its stroke. Fig. 6 is a detail per-

spective view similar to that shown in Fig. 5 with the thread engaging member in the position it occupies when the looper is at the forward end of its stroke.

The base plate 1 of the sewing machine is of the ordinary construction and has rising 60 therefrom the overhanging arm 2 in which reciprocates a needle bar 3 carrying needles 4, 4. The presser foot 5 co-operates with the feed dog 6 carried by the feed bar 7 which is operated by an eccentric 8 carried by the 65 main shaft 9. These parts are of the usual construction and will not therefore be described in greater detail.

The looper 10, which co-operates with the needle 4, is carried by the looper carrier 11 70 which in turn is mounted upon a looper supporting rod 12 carried in the bearings 13 and 14 supported on the base plate. This looper supporting rod in the operation of my machine is given an oscillating and also 75 a longitudinal movement. This movement of the looper supporting rod causes the looper after it has entered the needle loop to move laterally to position the looper thread loop for the entrance of the needle. 80

The looper supporting rod 12 is oscillated and moved laterally by the arm 13 which carries at its free end a spherical bearing engaging loosely a stud extending from a collar 14^a which is rigidly secured to the 85 looper supporting rod. The swinging arm 13 receives its movement from the rock shaft 15 which is mounted in a bearing on the base plate. The arm 16 of said rock shaft is connected by links 17 to the said 90 swinging arm. The rock shaft receives an oscillating movement from the needle lever extension 18 through the link 19.

The thread controlling mechanism for the 95 looper thread comprises a slack thread controller carried by the lever extension, a pull off member which in the present embodiment of my invention is carried by the feed bar and an auxiliary thread controller intermediate said pull off member and the main 100 slack thread controller. The main slack thread controller 20 is secured to the lower end of the needle lever extension as shown in Figs. 1 and 2 and has its lower end 21 bent at an angle to the said lever extension 105 and is provided with thread eyes 22, 22.

The pull off mechanism consists of a member 23 which is attached to the feed bar at

one side and is bent to extend across the front face of said feed bar where it is slightly deflected in order to form a retaining finger 24 for the looper thread.

5 The auxiliary thread controller as shown more clearly in Figs. 5 and 6 is formed by a member 25 which is secured to the looper supporting rod by means of the collar 14^a. This member 25 as shown in the drawings is 10 formed from a wire which encircles the set screw 26 which locks the collar 14^a to said looper support. The thread engaging member 25 is bent into the shape of a segment of a circle. This thread member oscillates 15 between the thread guides 27 and 28 which are formed in the thread guiding wire 29. Said thread guiding wire is secured to the looper supporting bearing 14.

In the operation of my machine, the looper 20 is caused to move forward rapidly to enter the needle loop, reaching the forward end of its stroke substantially at the time the needle is leaving the throat plate of the machine. The looper, through the relation of 25 the operating parts, is caused to dwell at the forward end of its stroke substantially while the needle is reciprocating above the work support. When the looper is moving backward, the needle is descending and consequently the needle lever extension 18, as 30 shown in Fig. 1 is moved to the right, causing the slack thread controller 20 to take up the slack produced in the looper thread by the backward movement of the looper.

35 When, however, the looper is moving forward, the slack thread controller 20 is necessarily moving to the left, as viewed in Fig. 1, thereby giving up slack to the looper. It sometimes occurs in high speed machines 40 that this slack, given up to the looper on its forward movement, is in excess of that required by the movements of the looper, and consequently the looper thread whips to the wrong side of the looper or needle, causing 45 a skipping of stitches. The purpose of my auxiliary thread controller, is to take care of the slack on the forward movement of the looper, so that the looper thread will be practically held taut during certain portions 50 of both the forward and backward movements of the looper. As the looper moves forward to enter the needle loop, the thread engaging member 25, which is carried by the looper support, engages the looper thread 55 passing through the thread guides 27 and 28, as shown in Fig. 5. A continued movement of the thread engaging member as the looper moves forward, causes the thread to ride up on the thread engaging wire, as shown in 60 Fig. 6, thereby taking up the slack that would otherwise be formed in the looper thread. The pull off member 23, receives its movement from the feed bar, and, therefore, when the feed bar is moved to feed the 65 fabric, looper thread is pulled from the

supply which is used in the formation of the next stitch. It will be noted that when the feed mechanism for the machine is adjusted so as to increase the length of feed that the stroke of the pull off member will be increased and a greater amount of thread drawn off. On the other hand, when the feed of the machine is decreased, less thread will be drawn from the supply.

The invention in its broader aspect is not limited to the construction shown; as many changes may be made in the construction set forth in detail, without departing from the main principles of the invention, and without sacrificing its chief advantages.

Having particularly described my invention, what I claim as new and desire to secure my Letters Patent is:

1. The combination with stitch-forming mechanism including an oscillating thread-carrying looper, of a thread-controlling device, means for operating the same for taking up the looper thread on the forward movement of the looper, and a second thread-controlling device, and means for operating the same for taking up the looper thread on the return stroke of the looper.

2. The combination with stitch-forming mechanism including an oscillating thread-carrying looper, of thread-controlling mechanism for the looper thread, comprising a main slack thread controller operating to take up the slack on the return stroke of the looper, an auxiliary slack thread controller operating to take up the slack in the looper thread on the forward stroke of the looper and a looper thread pull-off member operating to pull thread from the supply.

3. The combination with stitch forming mechanism, including an oscillating thread carrying looper, of thread controlling mechanism therefor, comprising a main slack thread controller, and an auxiliary thread controller intermediate the main slack thread controller and the looper coöperating with said main controller for taking up the slack in the looper thread during both the forward and return strokes of the looper; substantially as described.

4. The combination with stitch forming mechanism, including a needle lever, a looper and means for operating the same, a looper thread controlling mechanism comprising a main slack thread controller operated by the needle lever and an auxiliary slack thread controller operated by the looper mechanism; substantially as described.

5. The combination with stitch forming mechanism, including a needle lever, a looper and means for operating the same, a looper thread controlling mechanism comprising a main slack thread controller operated by the needle lever, and an auxiliary slack thread controller operated by the

looper mechanism, and a pull off member for the looper thread; substantially as described.

6. The combination of a stitch forming mechanism including an oscillating looper, a slack thread controller thereto, a feed bar, a thread engaging member operated by said feed bar, and means coöperating therewith to pull off thread corresponding to the movement of the feed bar.

7. The combination of stitch-forming mechanism including a looper, a looper-support, means for oscillating the looper-support about its axis, and for moving the same longitudinally, and a slack thread controller including a thread-engaging member mounted on said looper-support, and having a curved thread-engaging face, and means coöperating with said thread-engaging member; substantially as described.

8. The combination of a stitch-forming mechanism including a looper, a looper support, means for oscillating said looper sup-

port about its axis and for moving the same longitudinally, and a slack thread controller 25 including a thread engaging member mounted on said looper support, and stationary thread guides coöperating with said movable thread engaging member; substantially as described.

9. The combination with a stitch forming mechanism, including a looper, and means for oscillating the same, a slack thread controller operated by said looper operating mechanism for controlling the slack in the 35 looper on the forward stroke of the looper, said slack thread controller moving in a plane oblique to the axis of the looper support.

In testimony whereof I affix my signature, 40 in presence of two witnesses.

LANSING ONDERDONK.
